CLAIM

The ornamental design for an animal waste collection and storage system, as shown and described.

DESCRIPTION

FIG. 1 is a front-right side perspective view of an animal waste collection and storage system constructed in accordance with the new design.

FIG. 2 is a rear-right side perspective view of the animal waste collection and storage system constructed in accordance with the new design.

FIG. 3 is a left side elevational view thereof.

FIG. 4 is a right side elevational view thereof.

FIG. 5 is a front elevational view thereof.

FIG. 6 is a rear elevational view thereof.

FIG. 7 is a top plane view thereof; and,

FIG. 8 is a bottom plane view thereof.

The broken lines in FIGS. 1-8 illustrate portions of the animal waste collection and storage system and form no part of the claimed design.

1 Claim, 4 Drawing Sheets
